2,589,911

DEVICE FOR CUTTING A SLAB FROM A
BLOCK OF SOFT MATERIAL SUCH AS
BUTTER OR CHEESE

Maurice J. Weinberg, New York, N. Y.

Application September 13, 1947, Serial No. 773,818

7 Claims. (Cl. 30—117)

1

This invention relates to device for cutting a slab from a block of soft material, such as butter or cheese. It is particularly directed to a wire butter cutter or remover frame for cutting a top portion of pre-determined thickness from a block of butter or the like material projecting above a receptacle such as shown in my copending application Serial No. 773,817 filed September 13, 1947.

It is an object of the present invention to provide an improved wire cutter of the character described, in which the space between the leading wire and the wire adjacent to it is less than the spaces between adjacent pairs of the remaining wires, so that the wire next to the leading wire enters the bulk or block of butter more quickly and holds the bulk or block down against its tendency to lift.

Yet another object of this invention is to provide an improved device of the character described, so constructed that the wires may be tensioned without turning and hence without torsion being applied to the wires which often results in breakage.

Another object of this invention is to provide a device of the character described, including a frame having parallel shelf portions adapted to ride over the top of the flanges on the butter chamber, said shelf being provided with contact pins having half rounded portions projecting beneath the shelf to contact the top surface of the flanges. The advantages of such construction are as follows:

The cutting wires are prevented from rotating, hence preventing breakage of the cutting wires. The contact pins may be made of stainless steel and the wires are located somewhat below the shelf and in alignment with the rounded bottoms of the pins, thereby keeping the metal of the remover frame from contacting the flange of the butter chamber and hence preventing smudge which might be caused if the shelf would directly contact the top surface of the butter chamber. Furthermore, the frame may be made of magnesium alloy which might corrode but the stainless steel pins prevent contact between the magnesium frame and the butter chamber thereby eliminating likelihood of corrosion. Furthermore, the pins are hard and half rounded at the bottom and act as anti-friction members

2

thereby preventing friction between the remover device and the butter chamber.

Yet a further object of this invention is to provide a device of the character described formed with a hollow handle, thereby reducing weight. The cutter is furthermore so constructed that if a wire breaks, it can easily be replaced.

Still another object of this invention is to provide a strong, rugged and durable device of the character described, which shall be easy to manipulate, relatively inexpensive to manufacture, easy to assemble, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of the invention

Fig. 1 is a top plan view of a device embodying the invention;

Fig. 2 is a side elevational view thereof;

Fig. 3 is a cross-sectional view taken on line 3—3 of Fig. 1;

Fig. 4 is a front end view of the device shown in Fig. 1;

Fig. 5 is a cross-sectional view taken on line 5—5 of Fig. 1;

Fig. 6 is an enlarged cross-sectional view corresponding to one side of the structure shown in Fig. 5;

Fig. 7 is an end view of one of the wire anchoring devices; and

Fig. 8 is a top plan view of one of the wire anchoring devices.

Referring now in detail to the drawing, 10 designates a device embodying the invention. The same comprises a frame 11 which may be made of magnesium alloy or any other suitable material. Said frame 11 comprises a handle 12, which may be hollow or tubular in construction. At the front end of the handle 12 is a transverse member 13 extending to both sides of the handle. At the juncture of the handle 12 with the cross bar 13 is a downwardly extending substantially

semi-circular projection 14 serving as an abutment against which the index finger of the hand grasping the handle may press when using the device.

Extending forwardly from the ends of the cross bar 13 are a pair of parallel symmetrical side bars 15. Each side bar 15 is formed with an inwardly extending flange 16 having an under surface 17. The flange 16 is at the top of the side bar 15, thereby forming an inner surface 18 for the portion of the side bar which projects below flange 16. The side bars 15 are formed with a plurality of aligned pairs of through openings 19. The undersurface 17 is preferably somewhat above the axes of the through openings 19. At the inner end of each through opening 19 is substantially a semi-cylindrical notch 20 formed in surface 17 of each flange 16.

At the forward end of the side bars 15 are upwardly extending portions 30 interconnected by a cross bar 31 which is above the top surface of the side bars 15 to pass above the butter slab which is to be severed. There may be any suitable number of aligned pairs of through openings 19. However, the first two openings on each side bar 15 are more closely spaced than are the remaining openings 19 in said side bar.

Each side bar 15 is formed with a vertical through opening 33 registering with each opening 19, for the purpose hereinafter appearing. Furthermore, each flange 16 is formed between the notches 20 with vertical openings 35. Additional openings 35 may be formed in the flanges 16 in front of the leading opening 19 and in back of the rearmost opening 19.

Extending into each opening 19 is a wire tensioning sleeve or shank 40. Each sleeve 40 is formed with a longitudinal flat 41. It is also formed with a radial longitudinally extending slit 42 perpendicular to the flat 41. The sleeve 40 is furthermore formed with an axial opening 43 extending to the outer end of the sleeve, but terminating short of its inner end. Interconnecting opening 43 with the rear end of the sleeve, is an axial through opening of lesser diameter than the opening 43. The diameter of opening 44 is somewhat greater than the width of slit 42. The sleeve 40 is formed with external screw threads 45 extending from its outer end inwardly. Each sleeve 40 has its inner end inserted into one of the openings 19 with the threaded portion 45 protruding. Inserted in each opening 33 is a pin 46 contacting the flat to keep the sleeve 40 from turning within the opening 19. Screwed on the outer threaded portion 45 of sleeve 40 is a nut 47 contacting the outer surface 48 of side bar 15. Interconnecting each pair of opposite sleeves 40 is a cutting wire 50. The ends of the wire pass through slit 42. The ends of the wire are, furthermore, upset or formed into a head and engage shoulders 51 formed between the openings 43 and 44.

It will be noted that each sleeve 40 may slide within its opening 19. Thus by tightening the nuts 47, opposite sleeves 40 are moved in opposite directions and tend to tighten wire 50 supported thereby.

It will be noted that the leading wire is closer to next to the leading wire than are the remaining wires 50 from each other.

Fixed within each opening 35 is a pin 55 having a half rounded lower end projecting below surface 17. The underside of the pins 55 are

substantially in the plane of the wire 50 which are in turn substantially in the plane of the axes of sleeves 40.

It will be noted that the portions of the wire 50 beneath the flanges 16 are located below the notches 20 and hence do not contact said flanges. The pins 55 may be made of stainless steel or other hard, non-corrosive metal. Extending inwardly from the undersides of the side bars 15 are a pair of aligned lugs 60. The lugs 60 are located adjacent the front ends of the side bars 15. The upper surfaces of the lugs 60 are substantially at the level of the under surface of the side bars 15. Said lugs 60 are aligned with one another as shown in the drawing.

The device 10 is to be used in conjunction with a butter chip or pat making machine or device shown in my copending application Serial No. 773,817, filed September 13, 1947. In said co-pending application, there is disclosed a butter chamber open at its upper end and provided at the sides thereof and adjacent its upper end with parallel outwardly extending flanges to be engaged between the lugs 60 and the flanges 16. In said co-pending application, there is explained that a block or bulk of butter is projected above the upper end of the chamber. The cutter or remover 10 is engaged with the flanges on the chamber and moved across the open end of the butter chamber so that the wires 50 cut through the butter to sever a top slab from the block or bulk of butter in the butter chamber.

In cutting the top slab of butter, the block of butter has a tendency to lift when the first wire cuts in. For this reason, the second wire has been placed close to the first wire to hold down the bulk and preventing it from lifting.

It will be noted that the wire may be tensioned without turning the wire and without applying any torsion to the wire so as to prevent breaking of the wires. Since the lugs 60 are located only at the front end, it is only necessary to push the frame until the leading wire has cut through the butter. The cutter device may then be tilted upwardly and the top slab removed. It is not necessary to lift the device straight up vertically, and it is not necessary to stop the cutter device at any exact point as long as the lug 60 moves beyond the flanges of the butter chamber. The provision of the flanges 16 and the hardened pins 55 cause the cutter frame to ride horizontally on the butter chamber and thus prevents breakage of the wire. Furthermore, because of the provision of the pins 55, the wires are below the lower surfaces of the shelves or flanges of the cutter frame thereby keeping the metal of the remover frame from smudging the butter. Furthermore, the frame may be made of magnesium alloy or other metal which might corrode and yet the hardened, non-corrosive pins 55 prevent the magnesium frame from contacting the butter chamber and prevents corrosion. Since the pins are hard and half rounded at the bottom, they act as anti-friction members which facilitates cutting of the butter.

The hollow handle reduces weight of the device. If a wire breaks, it can easily be replaced. The wires may be made of stainless steel or piano wire or any other suitable material. Obviously, the pins 46 impinging upon the flat surfaces 41 prevent the turning of the sleeves 40.

It will thus be seen that there is provided a device in which the several objects of this inven-

tion are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

It will be noted that the forward ends of the shelves 16 act as locator portions to contact the top of the butter chamber to facilitate engagement of said device with the flanges of the butter chamber or the spreader flanges.

Having thus described my invention, I claim as new and desire to secure by Letters Patent:

1. A device of the character described comprising a hollow handle, a transverse bar at the front end of the handle extending beyond the opposite sides of the handle, parallel forwardly extending bars at opposite ends of the transverse bar, upwardly extending projections at the forward ends of said bars, a transverse bar interconnecting the upper ends of said upwardly projecting portions, the underside of said front transverse bar being above the plane of said side bars, said side bars being provided with inwardly extending longitudinal flanges having undersurfaces above the undersurfaces of said side bars, and a pair of lugs at the front ends of said side bars, projecting inwardly and spaced below said flanges, and transverse wires supported on and between said side bars.

2. A device of the character described comprising a hollow handle, a transverse bar at the front end of the handle extending to opposite sides thereof, parallel forwardly extending side bars at opposite ends of the transverse bar, upwardly extending projections at the forward ends of said bars, a transverse bar interconnecting the upper ends of said upwardly projecting portions, the underside of said front transverse bar being above the plane of said side bars, said side bars being provided with inwardly extending longitudinal flanges having undersurfaces above the undersurfaces of said side bars, and a pair of lugs at the front ends of said side bars, projecting inwardly and spaced below said flanges, said side bars being formed with a plurality of aligned pairs of through openings, sleeves having flats, within said opening, pins on said side bars engaging said flats to prevent said sleeves from rotating, the outer ends of said sleeves being screw threaded, nuts screwed to the outer screw threaded ends of said sleeves, each of said sleeves being formed with a longitudinal radial slit and an axial opening communicating with the slit and with an intermediate shoulder at the bottom of the slit and a wire interconnecting each pair of opposite sleeves and having end portions passing through the slits and engaging said shoulders.

3. A device of the character described, comprising a substantially rectangular frame, a handle on one end of said frame, said frame including parallel side bars, said side bars being formed with inwardly extending longitudinal flanges, said side bars being formed with pairs of aligned opposite through openings, sleeves slidably and non-rotatably mounted in said through openings, a wire interconnecting each pair of opposed sleeves, and means to slidably move said sleeves outwardly in opposite directions to tension the wires interconnected by said sleeves, said sleeves having longitudinal, radial slots receiving portions of said wires.

4. A cutter of the character described comprising a cutter frame having a handle and a pair of side bars, said side bars being formed with a plurality of pairs of aligned opposite openings, 5 a pair of coaxial sleeves slidably and non-rotatably mounted within each pair of opposite openings, said sleeves projecting beyond the outer surfaces of said side bars, wires interconnecting each pair of opposite sleeves, nuts screwed on the protruding ends of said sleeves and contacting the outer sides of said side bars, for tensioning said wires, each sleeve having a longitudinal radial slit, and being formed with an axial through opening communicating with said slit and each sleeve being provided with a shoulder in said through opening, and means on said wires engaging said shoulders so that when said nuts are turned the wires will be tensioned.

5. A butter cutter comprising a handle, a transverse bar at the front end of the handle extending to opposite sides thereof, parallel forwardly extending side bars projecting forwardly from opposite ends of said transverse bar, upwardly extending projecting portions at the forward ends 25 of said side bars, a front transverse bar interconnecting the upper ends of said upwardly projecting portions, the underside of said front transverse bar being above the plane of said side bars, said side bars being formed with a plurality of pairs of aligned opposite openings, a pair of coaxial sleeves slidably and non-rotatably mounted within each pair of opposite openings, said sleeves projecting beyond the outer surfaces of said side bars, the projecting portions of said sleeves having external screw threads, wires interconnecting each pair of opposite sleeves, and nuts screwed to the protruding ends of said sleeves and contacting the outer sides of said side bars for tensioning said wires upon turning said nuts, said side bars being provided with inwardly extending longitudinal flanges having undersurfaces above the undersurfaces of said side bars, each of said sleeves being formed with a longitudinal radial slit, and said sleeves each being formed with an intermediate shoulder at the bottom of the slit and said wires having heads at their ends to engage said shoulders so that when said nuts are turned, the sleeves will tension said wires.

6. A butter cutter comprising a cutter frame having a handle, a transverse bar at the front end of the handle extending beyond the opposite sides of the handle, parallel forwardly extending side bars projecting forwardly from opposite ends of said transverse bar, upwardly extending portions at the forward ends of said side bars, a front transverse bar interconnecting the upper ends of said upwardly extending portions, the underside of said front transverse bar being spaced above the plane of said side bars, said side bars being of angular cross-section and comprising top inwardly extending flanges and outer downwardly extending flanges, said inwardly extending flanges having undersurfaces extending to the front ends of the side bars, and a transverse cutting wire interconnecting said side bars and located beneath said inwardly extending flanges.

7. A butter cutter comprising a cutter frame having a handle, a transverse bar at the front end of the handle extending to opposite sides thereof, parallel forwardly extending side bars projecting forwardly from opposite ends of said transverse bar, upwardly extending portions at the forward ends of said side bars, a front trans-

verse bar interconnecting the upper ends of said upwardly extending portions, the underside of said front transverse bar being spaced above the plane of said side bars, said side bars being of angular cross section and comprising top inwardly extending flanges and outer downwardly extending flanges, said inwardly extending flanges having undersurfaces extending to the front ends of the side bars, a transverse cutting wire interconnecting said side bars and located beneath said inwardly extending flanges, and means to anchor the ends of said wire, and inwardly extending lugs spaced below said inwardly extending flanges on said side bars.
